DETERGENT COMPOSITION

Arthur J. I. Harding, Spartanburg, S.C., assignor to Deer-
ing Milliken Research Corporation, Spartanburg, S.C.,
a corporation of Delaware

No Drawing. Filed Mar. 9, 1960, Ser. No. 13,727

5 Claims. (Cl. 252—142)

This invention relates to novel textile treating compositions and to methods for their use.

According to this invention, one or more of the advantages described hereinafter are obtained by treating a textile fabric with an aqueous solution of a composition comprising a water soluble sulfonic acid condensation product of aldehydes and aromatic sulfonic acids, or the water soluble salts thereof, and a water soluble acidic material having a molecular weight of less than 300, in an amount sufficient to render the resulting aqueous solution initially acidic at a pH of less than about 5 but less than the amount which would injure the fabric.

It is an object of this invention to provide a composition which enhances the cleansing power of detergents.

It is another object to provide a composition which enhances the brightening and whitening properties of textile fluorescent brightening agents.

Still another object is to provide certain novel additive compositions for detergents.

A further object is to provide certain novel detergent compositions.

A further object is to provide a method of treating textile fibers to give at least one of a cleaner product, improved brightness and whiteness, improved hand, warmth, greater tear strength, a higher flex abrasion resistance, and improved tensile strength.

Other objects will be apparent to those skilled in the art.

It is well known in the art that many natural and synthetic fibers commonly used in textile fabrics yellow or otherwise discolor on exposure to sun and/or air. Many detergents presently on the market seek to overcome this effect by incorporating a fluorescent brightening agent or "optical bleach" in the detergent composition. These agents are often very expensive. The compositions of this invention enhance the brightening power of many of these agents and often permit a reduction in the amount of these expensive agents while at the same time maintaining the same degree of brightening properties.

It has also been found that the cleansing properties of detergents can be improved by incorporating therein a composition of this invention, while at the same time providing additional advantages to the resultant detergent composition.

In the textile art, one of the tests of the quality of a fabric is its hand or handle. The more expensive fibers are characterized by a soft, pleasing hand as exemplified by the more expensive grades of cottons and the cashmere wools. Unfortunately, washing textile fabrics with detergents or soaps seldom retains the hand present in the original product and more often produces a progressively poorer hand. A detergent incorporating the composition of this invention can reverse this trend toward a poorer hand and often can produce a better hand than was present in the fabric as originally prepared.

It is also known in the art that detergent washing of a fabric composed of natural fibers often reduces at least one of the tensile and tear strength and flex abrasion resistance of the fabric. It has been found that this deleterious effect of washing of textile fabrics, especially wool and cotton fabrics, with a detergent can be reduced by incorporating in the detergent the composition of

2

this invention. Moreover, the tensile strength can often be increased beyond that of the same fabric merely treated with water alone.

Textile fabrics which can be treated with the compositions of this invention include those comprising the natural proteinaceous fibers, e.g., wool, the natural cellulosic fibers, e.g., cotton and linen, the modified cellulosic fibers, e.g., viscose rayon, the cellulose acetates and ethers, and the man-made fibers, e.g., polymeric hexamethylene adipamides, e.g., the nylons, polyacrylonitriles including those sold under the trademark "Orlon," polymeric vinylidene chlorides and polyester fibers, e.g., polymeric ethylene glycol terephthalic acid esters, including those sold under the trademark "Dacron," mixtures of the above and mixtures with other fibers. The preferred fabrics are those consisting entirely of or containing a substantial amount, e.g., 40% or more, of wool or cotton. Particularly outstanding results are obtained with pure wool and pure cotton fabrics. The fibers used in the textile fabrics, especially cotton and wool, can be treated in the form of an unwoven mass or as threads or yarns and the treatment of these fibers in this form as well as in the knitted or woven form is within the scope of this invention.

25 All of the compositions and the process of this invention comprise using (1) a water soluble sulfonic acid condensation product of an aldehyde and an aromatic sulfonic acid, or a water soluble salt thereof, and (2) an acidic material having a molecular weight of less than 300.

Included in the compounds falling within the definition of (1), i.e., diarylalkane disulfonic acids and their salts, and preferred are the condensation products of an aldehyde and a carbocyclic aryl sulfonic acid, e.g., those having the general formula

wherein R is hydrogen, the ammonium (NH_4) radical, or a metal, preferably an alkali metal, e.g., sodium or potassium, "aryl" is a connecting carbocyclic aryl radical, e.g., phenyl, tolyl, xylyl, hydroxyphenyl, cresyl, sulfonyloxyphenyl, and n is an integer from 1-10, preferably 1. The aryl group can, in addition to the sulfonyloxy group, contain one or more substituents, e.g., amino, hydroxy, nitro, halo e.g., chloro, and sulfonyloxy. Included within this preferred class of compounds are the diphenylmethane disulfonic acids, dinaphthylmethane disulfonic acids, ditolymethane disulfonic acids, dixylylmethane disulfonic acids, di-hydroxyphenyl-methane disulfonic acids, dicresylmethane disulfonic acids, di-chloronaphthyl-methane disulfonic acids, di-nitronaphthyl-methane disulfonic acids, diphenylmethane-meta-tetrasulfonic acids and di-hydroxynaphthyl-methane disulfonic acids. This class of compounds are well known in the art and are described in more detail with further examples in Grasser and Enna, "Synthetic Tannins," paragraphs 35 to 68 (1922), Technical Press Ltd. They are prepared by the well known reaction of an arylsulfonic acid with an aldehyde, preferably formaldehyde, to produce a hydrocarbon bridge between two of the arylsulfonic acid molecules. It is possible, by employing a mixture of starting arylsulfonic acids, to produce a mixed sulfonic acid condensation product, i.e., one aryl group differs from the other connected aryl group. However, ordinarily 60 the disulfonic acid products are symmetrical. There are many of these disulfonic acid condensation products available commercially.

The acidic materials having a molecular weight of less than 300 which are employed in the compositions of this invention are limited to those compounds which are capable of lowering an aqueous solution thereof, in the presence of the selected condensation product, to a pH

of less than about 5, and preferably in an amount which will produce a pH higher than 2. This can readily be ascertained by testing various concentrations of the acidic material alone in an aqueous solution. As the other ingredient and/or ingredients of the claimed composition are preferably neutral or acidic, it will be apparent that the amount of a selected acidic material necessary to achieve the desired pH in the compositions of this invention will be about the same as, or slightly less, than the amount which alone will produce the desired pH. Similarly, the effect of the acidic material on a selected fabric at a particular concentration can be determined by tests well known in the textile art, e.g., tensile, tear and/or flex abrasion. These acidic materials preferably have a dissociation constant (pKa) of between about 5×10^{-2} and about 1×10^{-8} and more desirably between about 1×10^{-3} and about 1×10^{-6} .

The preferred acidic materials are, either organic or inorganic acids, i.e., as distinguished from acidic salts such as, for example, sodium acid sulfate. Examples of inorganic acids are sulfuric, phosphoric, and hydrochloric. It will be apparent to those skilled in the art that these acids, in high concentration, can injure many fabrics. For this reason, the organic acids are preferred and, in fact, ordinarily give superior results than are obtained with the inorganic acids, even when the latter is used in an amount which does not injure the fabric.

Examples of the organic acids which can be used in the process of this invention include acetic, formic, chloroacetic, dichloroacetic, benzenesulfonic, hydroxyacetic, p-toluenesulfonic, citric, lactic, tartaric, gluconic, and oxalic acid. Preferred are the carboxylic and especially the polyhydroxycarboxylic acids. Of these, citric acid gives outstanding results and is ordinarily preferred.

If the composition is intended for textile mill use, then the stronger, e.g., inorganic acids can be used, particularly if the fabric to be treated is wool. However, for home use, the organic acids and particularly the polyhydroxycarboxylic acids, especially citric acid, are preferred.

The amount of the above compounds which should be applied to the selected fabric can be varied over a fairly wide range. For example, good results can be obtained employing the condensation product in the range of about 0.01 to about 5%, calculated on the weight of the dry fabric being treated. Lesser amounts tend to diminish some of the advantages that are obtained by this ingredient whereas greater amounts tend to render the process commercially or economically unfeasible. Generally, between about 0.25 and 2.0% give the optimum desired results. Similarly, the amount of acid which can be employed can be varied considerably, e.g., from about 0.001 to 30%, and preferably between about 0.25 and 20%, and more desirably about 0.25 and 10%, calculated on the weight of the dry fabric. However, the amount used should be such that a 0.5% aqueous solution of the resulting composition will have an initial pH of between about 2 and about 5. The amount and nature of the acidic material should be such that the resulting composition will not injure the fabric to be treated at normal concentrations. It is preferred to operate at or below the isoelectric point of the wool, which is ordinarily around 4.5, but can range from about 3.7 to 5.2. The exact amount of each ingredient which should be employed will depend on the fabric being treated and, to a certain extent, on the results desired, with the usual proportion of condensation product to acidic material being from 1:100 to 6:1. For example, improved hand, improved tensile and tear strength, warmth, improved flex abrasion resistance, and elasticity will not always occur simultaneously and varying the amount of condensation product and acidic material will enhance each of these properties to a varying degree.

The compositions of this invention are preferably employed as additives for detergents, especially the anionic,

e.g., the alkylbenzene-sulfonic acid, and the nonionic, e.g., alkaryl polyglycol, detergents. Among the former are the compounds of the formula alkyl-phenyl- SO_3-M wherein alkyl is the alkyl radical of a fatty acid, and M is hydrogen or an alkali metal, which compounds comprise a well known class of anionic detergents and include sodium dodecylbenzenesulfonate, potassium dodecylbenzenesulfonate, sodium laurylbenzenesulfonate, sodium oleylbenzenesulfonate and sodium cetylbenzenesulfonate. Others are the alkali metal salts of the higher alkylsulfonic acids and the alkali metal dialkyl sulfosuccinates, e.g., sodium diethylsulfosuccinate, and sodium dihexylsulfosuccinate, sodium sulfoethylphthalate, sodium oleyl-p-anisidinesulfonate, sodium tetradecanesulfonate, sodium diisopropylnaphthalenesulfonate, sodium octylphenoxyethoxyethylsulfonate, etc., and the alkali metal alkyl sulfates, e.g., sodium lauryl sulfate. Ordinarily, the alkali metal salts, rather than the free acid detergents are preferred.

As nonionic detergents there can be employed alkyl-phenoxyethylene oxides, e.g., p-isoctyl phenol-polyethylene oxide (10 ethylene oxide units), long chain alcohol-ethylene oxide condensation products, e.g., dodecyl alcohol-polyethylene oxides having 4 to 16 ethylene oxide units per molecule, polyglycerol monolaurate, glycol dioleate, sorbitan monolaurate, sorbitan monostearate, sorbitan monopalmitate, sorbitan monooleate, sorbitan sesquioleate, the condensation products of ethylene oxide with sorbitan esters of long chain fatty acids (Tweens), etc.

The preferred detergent to be employed with the compositions of this invention are the alkali metal salts of the alkylbenzenesulfonates, especially sodium dodecylbenzenesulfonate.

As stated hereinbefore, the compositions of this invention enhance the whitening and brightening characteristics of detergent additives known as textile fluorescent brightening agents. Thus, the detergent compositions of this invention preferably comprise these agents, employed in the amounts normally used in detergents or in somewhat lesser amounts, because of the enhanced properties of these agents.

As the fluorescent brightening agent there can be employed any of the conventional ones, such as those mentioned in "Colour Index, Society of Dyers and Colourists, The American Association of Textile Chemists and Colorists," vol. 2, pages 2909-2922, and volume 3, pages 3341-3342 (1957). Preferred are the brightening agents having one or more amino groups in the molecule or other radical having basic characteristics. The particular fluorescent brightening agent employed will depend on the textile fabric being treated, in accordance with the recommendations in the Colour Index.

In the textile art, the brightening agents are generally classified as cotton, wool, and all-purpose brightening agents. Usually, with wool a stilbene group containing fluorescent agent is employed, but as above-indicated other fluorescent agents can be used. If the detergent composition is to be used to treat both wool and cottons, both a wool and a cotton or an all-purpose brightening agent can be employed.

There can be incorporated in a detergent composition comprising a condensation product and acidic material as defined hereinbefore, various filling agents, e.g., Glauber's salt, sodium chloride, potassium chloride, sodium hexametaphosphate, sodium pyrophosphate, monosodium phosphate, disodium phosphate and trisodium phosphate.

There can also be included suspending agents such as lignin sulfonic acid and methyl cellulose, and bleaching agents, e.g., sodium chlorite.

In using the compositions of this invention, the usual textile scouring or home washing methods can be employed. The increases in tensile strength of cellulosic fabrics become more readily apparent at temperatures above 60° C., although increased tensile strength becomes apparent in wool at lower temperatures. With woolen

fabrics, improved flex abrasion resistance often is at an optimum at higher temperatures, e.g., from 85-100° C. However, increased cleansing power of a detergent, increased brightening power of a fluorescent brightening agent and improved hand and texture can be noted at almost any temperature.

A usual procedure involves agitating the fabric in a solution of the composition at the desired temperature, usually at a liquor ratio of from 10 to 50:1 for from about 5 minutes to one hour. A washing or scouring time of about 20-30 minutes is ordinarily adequate, especially if very hot water is used. The fabric can then, if desired, be rinsed thoroughly and then dried.

The fabric can then be tested, if desired, for the enhanced properties described hereinbefore. Hand or handle is a subjective factor. A pleasing hand is one approaching the feel or handle of cashmere, in the case of woolens, and of long staple Egyptian cotton, in the case of cottons. In the examples hereinafter, the fabrics described were tested for tensile and tear strength and flex abrasion resistance by accepted tests on standard equipment.

In the examples below, all percentages are by weight.

Example I

A 100 g. piece of dirty woven woolen cloth was washed in 2 liters of warm water containing 6 g. of a detergent composition having the following composition:

	Percent
Detergent (sodium dodecylbenzenesulfonate)	37.5
Citric acid	33.5
Formaldehyde-arylsulfonic acid condensation product (Erional NW acidic)	8.0
Fluorescent brightening agent (Uvitex W.G.S.)	4.0
Filler (Glauber's salt) and water	17.0

The fabric was rinsed thoroughly and dried. It was found to be cleaner, brighter and to have a better hand than another sample of the same fabric washed in a corresponding detergent composition in which the citric acid and condensation product was replaced by filler.

Similarly, 225 g. of the above composition will wash a 3.75 kg. load of mixed laundry in an agitator type automatic washing machine or the corresponding weight of delicate fabrics by hand to give a cleaner, brighter wash than the corresponding detergent without the citric acid and formaldehyde-arylsulfonic acid condensation product. Each, some, and all of the following changes in the above composition can be made while retaining the increased detergency, brightening and other desirable properties of the detergent composition:

- (a) Part of the filler can be replaced by suspending agent, e.g., 0.5% lignin sulfonic acid;
- (b) The detergent can be varied from about 30% to about 43% with corresponding changes in the percentage of filler;
- (c) The Uvitex W.G.S. can be replaced by Tinopal BVA or an equal proportion of each employed, or the fluorescent brightening agent eliminated;
- (d) The sodium dodecylbenzenesulfonate can be replaced with sodium oleylsulfate, sodium laurylsulfate, sodium octadecylbenzenesulfonate, or replaced partially or completely with a nonionic detergent, e.g., Tergitol NPX alkaryl polyglycol;
- (e) The Erional NW can be replaced by dinaphthylmethane disulfonic acid, dicesylmethane disulfonic acid, or other carbocyclic diarylalkane disulfonic acid;
- (f) The citric acid can be varied from about 15% to about 45%;
- (g) The citric acid can be replaced by lactic acid;
- (h) The citric acid can be replaced by tartaric acid;
- (i) The formaldehyde-arylsulfonic acid condensation product can be varied from about 4% to about 25%, with corresponding changes in the proportion of filler.

Example II

A 100 g. sample of dirty woven woolen cloth was washed in 2 liters of 60° C. water containing 6 g. of a commercial detergent composition consisting of a wool fluorescent brightening agent, about 43% sodium dodecylbenzenesulfonate, and filler; 3.0 g. of citric acid, and 0.5 g. of Erional NW. The washed fabric was cleaner, brighter, and had a softer hand than an identical sample identically washed in water containing 6 g. of the commercial detergent only. It also had increased tensile strength compared with the cloth washed in commercial detergent only.

Example III

15 Following the procedure of Example II, but boiling the cloth in the detergent compositions, the woolen cloth washed in the mixture containing citric acid and condensation product had greater flex abrasion resistance than the cloth washed in commercial detergent only and the starting unwashed cloth.

Example IV

25 The following are detergent compositions intended primarily for mill use to clean and brighten woven and knitted woolen fabrics and yarn and to improve their hand, tensile strength and/or flex abrasion resistance.

A. Detergent:

	Percent
Tergitol NPX (alkaryl polyglycol nonionic detergent)	12
Sodium dodecylbenzenesulfonate	6
Citric acid	61
Formaldehyde-arylsulfonic acid	16
Condensation product Erional NW (acidic)	16
Fluorescent brightening agent Uvitex WGS	5

B. Detergent:

40	Tergitol NPX	21
	Sodium dodecylbenzenesulfonate	10
	Citric acid	41
	Erional NW (acidic)	20
	Uvitex WGS	8

C. Detergent:

45	Tergitol NPX	14.5
	Citric acid	58
	Erional NW (acidic)	21.7
	Uvitex WGS	5.8

50 A 100 g. sample of woven woolen greige fabric was washed at 70° C. for 20 minutes in 2 liters of water containing 8.15 g. of detergent composition A. It was then rinsed thoroughly and dried. The washed fabric was cleaner, brighter, and had greater flex abrasion resistance than the control sample washed only in the same amount of Tergitol NPX and sodium dodecylbenzenesulfonate as was present in composition A.

60 A 100 g. sample of woven woolen greige fabric was washed at 60° C. for 30 minutes in 2 liters of water containing 4.9 g. of detergent composition B. The washed, rinsed and dried fabric was cleaner, brighter and had greater tensile strength and flex abrasion resistance than an identical sample washed only in the same amount of Tergitol NPX and sodium dodecylbenzenesulfonate as was present in composition B.

65 Similarly, another 100 g. sample of the same fabric was washed with detergent composition C at 60° C. for 30 minutes to produce a washed fabric that had markedly superior flex abrasion resistance, without loss of tensile strength, when compared with an identical sample washed with the same detergent, but without the citric acid and condensation product.

Example V

70 The following is a detergent composition suitable for

washing cotton fabrics as well as woven and knitted woolen fabrics.

Detergent:

	Percent
Sodium dodecylbenzenesulfonate	35
Citric acid	35
Formaldehyde-arylsulfonic acid condensation	8.75
Product Erional NW (acidic)	4.25
Fluorescent brightening agent Tinopal BVA	4.25
Filler (neutral mixture of Glauber's salt and phosphates) and water	17

Soiled cotton fabrics washed in the above detergent composition display considerably greater brightness and appear cleaner than comparable fabrics washed in a comparable amount of a detergent composition in which the citric acid and condensation product have been omitted.

Each, some and all of the following changes in the above composition can be made while still retaining the enhanced properties thereof.

- (a) The detergent can be varied between about 17% and about 45% with corresponding variations in the filler;
- (b) The citric acid can be varied between about 10% and about 40% with corresponding variations in filler and/or detergent;
- (c) The condensation product can be varied between about 5% and about 15% with corresponding variation in filler and/or citric acid;
- (d) The fluorescent brightening agent can be varied between about 2% and about 9%, with corresponding variations in filler;
- (e) A nonionic detergent e.g., Tergitol NPX alkaryl polyglycol, can be substituted in the same or lesser proportions for the sodium dodecylbenzenesulfonate or added to the detergent composition with a corresponding reduction in filler;
- (f) The sodium dodecylbenzenesulfonate can be replaced by sodium oleylsulfate.

Example VI

A detergent composition corresponding exactly to that described in Example V, except that the formaldehyde-arylsulfonic acid condensation product was dinaphthylmethane disulfonic acid, was used in the same amount to wash dirty cotton fabric. The washed fabric was cleaner, brighter and had better strength than samples

of the same fabric washed in a comparable amount of detergent in which the citric acid and condensation product was eliminated.

What is claimed is:

- 5 1. A detergent composition consisting essentially of (1) from 14.5% to 45% of a detergent selected from the group consisting of synthetic organic non-soap anionic and nonionic detergents, (2) from 4 to 25% of a compound selected from the group consisting of a water soluble condensation product of formaldehyde and a carbocyclic aryl sulfonic acid, and a water soluble salt thereof, and (3) an amount, from 10% to 45%, of a hydroxy organic acid selected from the group consisting of citric acid, lactic acid and tartaric acid sufficient to render a 0.5% aqueous solution of the detergent composition initially acidic at a pH of between about 2 and about 5, the proportion of (2) to (3) being from 1:100 to 6:1.
- 10 2. The detergent composition of claim 1 wherein the hydroxy organic acid is citric acid.
- 20 3. The detergent composition of claim 1 wherein the condensation product is the water soluble condensation product of formaldehyde and naphthalene sulfonic acid.
- 25 4. The detergent composition of claim 1 containing from 2% to 9% of a fluorescent brightening agent.
- 30 5. A detergent composition consisting essentially of (1) from 17% to 45% of sodium dodecylbenzene sulfonate, (2) from 5% to 15% of the water soluble condensation product of formaldehyde and a carbocyclic aryl sulfonic acid and (3) an amount, from 10% to 40%, of citric acid sufficient to render a 0.5% aqueous solution of the detergent composition initially acidic at a pH of between about 2 and about 5, and (4) from 2% to 9% of a fluorescent brightening agent, the ratio of (2) to (3) being from 1:100 to 6:1.
